J. DAVIS

DOORSTOP

Filed Oct. 22, 1920.

INVENTOR
Joseph Davis
BY John H. Preng
ATTORNEY.

UNITED STATES PATENT OFFICE.

JOSEPH DAVIS, OF PITTSBURGH, PENNSYLVANIA.

DOORSTOP.

Application filed October 22, 1920. Serial No. 418,036.

To all whom it may concern:

Be it known that I, JOSEPH DAVIS, a citizen of the United States, residing at Pittsburgh, in the county of Allegheny and State 5 of Pennsylvania, have invented a new and useful Improvement in Doorstops, of which improvement the following is a specification.

My invention relates to improvements in 10 door checks or stops, applicable to swinging doors, and particularly to garage and such like doors.

The object of the invention is to produce 15 a simple and efficient door stop, which can be readily applied and cheaply constructed.

I accomplish this object by means of the device hereinafter described, reference being had to the accompanying drawings, forming part hereof, in which—

20 Fig. 1 is a side elevation of the device attached to the inner lower side of a door.

Fig. 2 is a front elevation of the same.

Fig. 3 is a plan view of the same.

Fig. 4 is a side elevation, showing the 25 device in inoperative position.

Fig. 5 is a front elevation of a modification of my device applied to a door.

Fig. 6 is a side elevation of the same, the stop being in inoperative position.

30 Referring to said drawings, 1 is a door on the inner lower side of which is suitably secured the member, 2, formed of a single plate of sheet steel or iron of suitable thickness or gauge to insure strength and resiliency therein. The sides and lower end of said plate are bent up to form the flanges, *a*, and the extreme upper end of said plate is provided with outwardly projecting extensions at right angles to the sides which

40 when bent upwardly in alignment with the flanges *a* form flexible fingers 3. A member, 4, formed of angle iron or steel, is pivotally mounted upon a pin, 5, journaled in the said flanges, *a*, the said flanges being

45 also a guide for said member or prop 4, the lower end of said member, 4, having a sharpened point adapted to engage in the

earth or other surface for the purpose of holding the door in open position. The flange *a*, on the lower end of the member, 2, 50 serves to limit the movement of said member, 4, towards the door and to hold the same in operative position.

In Figs. 5 and 6, I show a modified form of the device. In said figures, the member, 55 2, is provided with retention fingers similar to fingers 3 and at the lower end with lateral extensions having bolt or screw holes to enable the same to be fastened upon the door. The extreme lower end of the side flanges are provided with lugs or fingers, *c*, the ends of which are turned inwardly and form a stop, to limit the movement of the member, 4, towards the door, and hold it in 60 operative position.

65 The device described is made of a single sheet of steel of sufficient resiliency to enable the flexible fingers 3 to grasp and hold the member 4 in inoperative position, as shown in Fig. 4.

70 It is believed that the operation of the device can be readily understood from the preceding description, in conjunction with the drawings.

Having described my invention, what I 75 claim and desire to secure by Letters Patent, is:

A door stop comprising a member formed of a single plate of metal and a prop rod pivotally secured in said member, the said member having integral outwardly projecting resilient fingers adapted to hold said prop rod in inoperative position, and means at the lower end of said member to limit the movement of the said rod inwardly toward 80 the door.

85 In testimony whereof, I have hereunto signed my name in the presence of two subscribing witnesses.

JOSEPH DAVIS.

In the presence of—

D. HOMER WOOLLEY,
LOUIS B. SNYDER.
